UNITED STATES PATENT OFFICE.

THOMAS GATCH MELISH, OF CINCINNATI, AND MILTON WALLACE GATCH, OF MANSFIELD, OHIO, ASSIGNORS TO THE BROMWELL BRUSH & WIRE GOODS COMPANY, OF CINCINNATI, OHIO, A CORPORATION OF OHIO.

WIRE STRUCTURE.

957,619.

Specification of Letters Patent. Patented May 10, 1910.

Application filed November 29, 1907. Serial No. 404,336.

To all whom it may concern:

Be it known that we, THOMAS GATCH MELISH and MILTON WALLACE GATCH, citizens of the United States, and residents, respectively, of Cincinnati, in the county of Hamilton and State of Ohio, and of Mansfield, in the county of Richland and said State of Ohio, have jointly invented new and useful Improvements in Wire Structures, of which the following is a specification.

This invention relates to wire-structures and more especially to those adapted for use in the manufacture of rat-traps, grading-screens and the like, and its object is to provide a channeled rib having side flanges or feet along its open edges and notched openings having integral clips or flaps adapted to close or fold upon intersecting mesh-wires seated in said notched openings, whereby an extremely simple, readily made and applied structure is formed.

In the accompanying sheet of drawings, Figure 1 is a fragmentary plan view of a wire-structure embodying the invention herein, a few mesh-wires being shown seated and secured in place in several parallel strengthening ribs; Fig. 2, a perspective view of a fragmentary portion of a strip of metal showing the manner in which it is prepared prior to forming into its final channeled rib-shape, the clips or flaps being shown in their open position and the dotted lines in the view showing wherein the strip is bent to channel and strengthen the same and to present the notches in their wire-seating position; Fig. 3, a perspective view of a fragmentary portion of a rib constructed ready for use; and Fig. 4, a transverse section taken on the dotted-line *a*, *a* of Fig. 3, but with the clip or flap shown in seating-place on a mesh-wire, (the latter not being shown in Fig. 3.)

In these views, 1 indicates a flat strip of metal from which the rib is derived; 2, each one of a series of upturned clips or flaps along said strip of metal, openings 3 resulting in said strip when the metal is cut along three edges to form said clips or flaps 2; 4, notches made in the strip along the

side edges of said openings 3; and 5, 5, lateral feet or flanges extending from the open edges of the rib when the latter is made into grooved or channeled form, as shown at 6, by bending the strip along the series 55 of parallel dotted-lines seen in Fig. 2.

When the channeled and flanged rib has been formed, the said notches 4, 4 are disposed upward at either side the respective openings 3 to receive and seat the mesh-wires 7 at the intersections of the latter with the respective ribs. The mesh-wires having been duly seated in the respective notches 4, the clips or flaps 2 are each bent forward and laid down in contact with the said 60 mesh-wires so as to firmly secure the latter in their seated or locked position, free from any lateral or undue torsional strain or accidental displacement.

In Fig. 1 is shown a series of parallel 70 mesh-wires secured in seated-place in several adjoining parallel ribs, except that one of the clips or flaps in the rib to the left is not downturned or laid flat on the lowermost mesh-wire and, also, that three of the 75 clips or flaps in the rib to the right have not been downturned, nor is the lowermost wire extended into seating or locking place in said latter-named rib. This manner of illustrating the structure is believed to bring 80 out the invention herein to the best advantage and to more distinct view.

The channeled form of rib having the side flanges or feet 2 is extremely simple and strong and is especially adapted to 85 straight or flat work where stiffness is most desired, although it is well adapted to ordinary curved work of easy arc. The said flanges or feet 2 form broad or extended side bearings or platforms along the open 90 edges of the channeled-rib for the mesh-wires to firmly rest on and they take more or less strain off the notched portions of the channeled part of the rib.

We claim:

As a new article of manufacture, a device of the character described comprising a plane channeled-rib having a series of openings at suitable intervals apart therein, lateral flanges or foot-extensions along the 100

open side edges of said channeled-rib, a series of clips or flaps respectively provided adjacent said openings in the channeled-rib, transversely-alined notches in said rib lateral to said openings and adapted to receive mesh-wires in a completed wire-structure with said clips or flaps closed over said

mesh-wires at intersections to close the latter in place.

THOMAS GATCH MELISH.
MILTON WALLACE GATCH.
